UNITED STATES PATENT OFFICE.

JOHN A. BRILL AND WALTER S. ADAMS, OF PHILADELPHIA, PENNSYLVANIA; SAID ADAMS ASSIGNOR TO SAID BRILL.

CAR-TRUCK.

SPECIFICATION forming part of Letters Patent No. 739,802, dated September 22, 1903.
Application filed June 7, 1901. Serial No. 63,496. (No model.)

To all whom it may concern:

Be it known that we, JOHN A. BRILL and WALTER S. ADAMS, citizens of the United States, residing in the city and county of Philadelphia, State of Pennsylvania, have invented certain new and useful Improvements in Car-Trucks, of which the following is a specification.

Our invention relates to improvements in car-trucks, and although not limited in some of its features to any one class they have special reference to those known as "pivotal" trucks and on which the propelling-motor is carried. Among its objects may be mentioned the provision of a truck having a very short wheel-base and at the same time a long spring-base for the motor-supporting frame, a novel combined spring cap or pedestal, a new spring-support for the bolster, and a new and improved truck which shall be durable, compact, and efficient for the purposes required.

To the accomplishment of these objects and such others as may hereinafter appear the invention consists in the parts and combinations of parts fully described, and set forth in the claims appended hereto, reference being had to the accompanying drawings, forming a part hereof, in which the same reference characters represent like parts throughout, and in which—

Figure 1 is a side elevation of the truck embodying our improvements. Fig. 2 is a plan view of the same. Fig. 3 is an end view, the left half being a cross-section on a plane substantially through the center of the truck. Fig. 4 is a detailed perspective view of the connection of the transoms and side members of the frame and the bolster with its supports. Fig. 5 is an enlarged sectional view on the line $x-x$, Fig. 6, showing the bolster-support at one end and taken longitudinally through the bolster. Fig. 6 is a similar view transversely through the bolster-supporting bearings, and Figs. 7 and 8 are respectively elevation and plan views of another form in which the equalizing-bar spring is located within the wheel-base.

In the figures, 2 and 3 denote the axles and wheels of the truck, which are journaled in the axle-boxes 4, the latter being formed with depending lugs 5, preferably formed integral

therewith and provided with longitudinal apertures through which the equalizing-bars 6 extend and by which they are supported and connected with the axles. The equalizing-bars, as shown, are preferably rectangular in cross-section, placed on edge, and of such dimensions as to give ample strength and are simply straight iron bars from end to end, which form results in a very simple and cheap bar, besides allowing a low-hung frame. The apertures through which they project in the boxes have curved upper edges or faces 7 (shown in dotted lines in Fig. 7) to provide for a limited play in case one axle-box rises 65 or falls more than another. These boxes are simple, and therefore cheap to manufacture.

The axle-boxes are connected with the truck-frame by means of the inverted-U-shaped axle-box pedestals or yokes 8, whose vertical side members 9 and 10 embrace the said boxes in the usual or desired way, the axle-boxes, except in the respect mentioned, being of any ordinary or preferred type, and whose outer depending arms 11 are connected together by the angle-iron end pieces or cross-bars 12 of the truck-frame, which are bowed or bent out, as at 12^a, to accommodate the motor, the yokes being connected together on each side of the truck by the upper chords 13, 80 bolted to the tops of the yokes, and the lower angle-iron chord 14, also bolted to the inner depending arms 10^a of said yokes, the said chords, and consequently the side frame, being braced by the inclined or truss bars 15, 85 made, preferably, in one piece extending from the tops of the yokes, where they are secured by the same bolts as the chords 13, down to the middle of the lower chords and are bolted thereto. To render this connection convenient, the yokes, which are cast, forged, or otherwise constructed, are grooved or slotted on top, as at 8^a, to accommodate the said chords and braces and are provided with short inwardly-extending arms 10^a, adapted to be 90 bolted to the outwardly-extending horizontal flanges 14^a of the lower chord 14. The side members 9 and 10 of each yoke are rigidly connected together to strengthen them by the removable tie-bar 16, and which may be detached to allow the boxes to be removed therefrom. So far as some features of the invention

- tion are concerned the side members of the frame may be constructed integrally with the yokes or otherwise, but are preferred as shown.
- 5 The yoke-frame is spring-supported from the equalizing-bars 6, and as a means for simply and conveniently doing this the pedestals 8 (see Fig. 7) are provided with integrally-formed inverted spring recesses or 10 cups 17, which are virtual extensions of the axle-box openings, although a slight web may be interposed, if desired, said recess 17 being located over the said equalizing-bar, which carries a base block or cap 18, secured there- 15 to by a bolt and provided, if desired, with a lug 18^a, between which cap and lug and the bottom of the inverted cup 17 the coil-spring 19 is placed. The vertical arms 10 of the pedestals are cut away or notched, as at 20, 20 Fig. 3, and the inner cylindrical wall of the recess 17 may be likewise cut away to allow the truck-frame to move down over the equalizing-bar when the spring is compressed, a corresponding space 20^a being provided between the tops of the axle-boxes and the 25 yokes. An opening 21 is also provided in the cup-wall. This combined construction of the pedestal and spring-recess renders it a strong, cheap, and simple means for accom- 30 plishing the desired ends, besides serving as a covering and confining means for said springs, and dispenses with the extra bearing-block for the frame similar to the block 18 on the bar 6. These equalizing or car 35 springs may be placed on the inner side of the pedestals, as shown in Figs. 7 and 8, in which case it is a desideratum to place them as far apart and as close to the axles as possible to provide a more extensive spring-base 40 for the truck-frame. The described construction allows the springs to practically abut the boxes. In other constructions, as where a short wheel-base is preferred and the motors are supported outside the same, it is desir- 45 able to also support the motor-frame outside the wheel-base to provide a steadier support for the motor. The construction shown in Figs. 1, 2, and 3 offers a convenient method of so locating the springs and at the same 50 time retaining the advantages that accrue from a combined pedestal and spring-cup structure. Here the equalizing-bar 6 is ex- tended through and beyond the axle-box be- 55 neath the spring-recess 17, formed in the outer arm 11, a block 18 being secured to the end of the bar to support the spring. The construction is substantially the same as the other, except for the location of the spring- 60 cup on the other side of the yoke. Of course this receptacle may be formed at any other point along the arms 11, the bars 6 being correspondingly extended, and the detailed construction may be varied largely; but all these we hold within the scope of our invention.
- 65 The motors (not shown) are adapted to be sleeved upon the axles and are supported at
- their heels or free ends from the cross-bars 22, spring-supported at their ends upon the end bars 12 of the truck-frame, their ends being twisted to stand horizontally and perfor- 70 at 23^a, to raise the supporting parts above the flanges of the angle-iron end pieces 12. Coil-springs are placed both above and below the ends of the motor-support on the bolt 23 to 75 cushion its movement in either direction. This feature of supporting the free end of a motor inside or outside of the wheel-base on a frame which is itself spring-supported outside the wheel-base we consider broadly new 80 and intend so to claim it. This motor-supporting frame need not be the yoke-frame, but may be any other suitable for the purpose. Of course it will be understood that trucks, as shown, may be constructed, or one 85 set of springs may be placed inside the wheel-base and the other outside thereof.
- In order to pivotally connect the truck with the car-body, a novel bolster arrangement and connection is provided. The bolster 24, con- 90 sisting, preferably, of a stick of timber, as shown, having the usual pivot or center plate 25 and side bearing or rub plates 26, extends transversely of the frame and is confined be- 95 tween the angle-iron transoms 27 and 28, also 100 extending between said side frames, each with a vertical web against the side of the bolster and the horizontal web on top and extending away from the bolster. The side bearing or rub plates 26 may be adjustable in height, as 105 shown, and are preferably those shown and described in the patent to Walter S. Adams, bearing date of September 16, 1902, and num- 110 bered 709,071. The horizontal webs of these transoms are bolted to the top chords 13 of 105 the side frames, while the vertical webs are secured by the bolts 29 to brackets 30, formed integrally on the vertical side members of rec- 115 tangular braces or supports 31, which are se- 120 curely held between the top and lower chords 110 of the side frame, said brackets projecting in- 125 wardly along the side of the transoms 27 and 28, the ends of the bolster 24 being recessed, as at 32, to give room for the said brackets. These rectangular frames 31, under which the 130 braces 15 are adapted to pass, are of cast or wrought iron and are grooved at the top and bottom to fit said upper and lower members or chords of the side frame, to which they are securely bolted. They also have a web 31^a 135 with an elliptical aperture therein. This connection of the transoms with the other parts makes a most substantial and rigid construc- 140 tion.
- The novel means for flexibly supporting the 145 bolster consists of links or link-bars 33, ca- 150 pable of a slight swinging movement, which are suspended from pins 34^a, journaled in bearing-plates 34, bolted on top of the hori- 155 zontal flanges or webs of said transoms, near 160 the ends thereof, holes 33^a therethrough be- 165 ing provided for the said links, which extend

beneath the said bolster for some distance, and the opposing ones are connected together by pivot-bolts 35, on which are journaled (see Fig. 5) the ends of the upper half of an elliptic or semi-elliptic spring 36, the middle point of which bears against and may be secured to the under side of the bolster.

The spring 36 of course extends longitudinally of the bolster, as shown, and bears upward against it, substantially at its middle point. As a means of securing it thereto, if such construction is preferred, the means shown in Figs. 3 and 4 may be employed, which means consists of the plate 36^a, attached to 15 and let into the under side of the said bolster 24 and having a socket 36^b, adapted to receive the central band 36^c of the elliptic spring 36. Other means could obviously be utilized. To assist in supporting the bolster 24, coil-springs 20 37 are placed between the said bolster and pivot-bolts 35, centering-lugs and pivot-plates 38 being provided near its ends for the top of the springs, while corresponding lugs and blocks or saddles 39 are pivoted on the bolts 25 or pins 35 for the lower ends of the coil-springs 37, which blocks 39 are hollow or, as shown, straddle the ends of the elliptic springs 36. The links, as shown, are bossed at the ends to provide a longer bearing on their pivot-30 pins. The bolster is thus spring-supported at the ends and at the middle, which springs conjointly act in such supporting capacity, and at the same time either the end set or the middle spring is capable of performing that 35 function alone, whereby an added security against total disabling is provided should one set fail, and a better-acting bolster throughout is obtained. This method of supporting a bolster in its broadest embodiment we consider novel. Several longitudinal springs 40 could of course be used side by side, or the coil-spring might be replaced by others, or even a complete set of such springs of slightly smaller size could be placed at each end of 45 the bolster; but all such modifications and changes we consider within the limits of our improvements.

It will be apparent to those skilled in the art that various and many changes from the 50 described construction may be made and still fall within the bounds of our invention, and we therefore do not wish to be limited to such construction; but

What we claim as our invention, and wish 55 to secure by Letters Patent, is—

1. In a car-truck, the combination with a frame having axle-box yokes or pedestals, of axle-boxes in said pedestals, equalizing-bars suspended from said boxes, and springs interposed between said equalizing-bars and said pedestals, supporting the same outside the wheel-base of the truck.

2. In a car-truck, the combination with the truck-frame and yokes or pedestals carried 60 by said frame, provided with recesses outside of the wheel-base of the truck; of axle-boxes

in said pedestals, equalizing-bars suspended from said axle-boxes, and springs seated in said recesses and supported by said equalizing-bars.

70

3. In a car-truck, the combination with a truck-frame, and yokes or pedestals having recesses formed therein outside the wheel-base of the truck; of axle-boxes embraced by said yokes, apertured lugs depending from 75 said axle-boxes, equalizing-bars passing through said perforations, having their ends extending beyond the wheel-base of the truck, a spring-seat mounted upon the ends of said bars, and springs resting upon said spring-seat and resting in said recess to support said frame, outside the wheel-base.

4. In a car-truck, the combination with the frame, yokes or pedestals carried thereby, and outwardly-extending arms, recesses being formed between said pedestals and arms, of axle-boxes embraced by said pedestals, depending apertured lugs carried by said axle-boxes, an equalizing-bar passing through 80 said apertured lugs and extending between 90 the axle-boxes upon each side of the truck, spring-seats carried by the extended ends of said bars, and springs located in said recesses and resting upon said spring-seats, for supporting the truck outside of the wheel-base. 95

5. In a car-truck, the truck-frame comprising axle-boxes, yokes or pedestals embracing said boxes, an upper chord connecting the pedestals at their upper ends, a lower chord connecting said pedestals near their lower portion, a truss-bar secured to the upper ends of said pedestals beneath said upper chord, said truss-bar being secured to said lower chord at the center thereof, a rectangular frame secured in place between said upper chord and 100 said truss-bar, depending apertured lugs carried by said axle-boxes, equalizing-bars passing through said apertured lugs, and extending beyond the wheel-base of the truck, and 105 springs supported upon the extended ends of 110 said equalizing-bars supporting said truck-frame.

6. In a car-truck, the combination with a frame having axle-box yokes or pedestals, of 115 axle-boxes embraced by said pedestals, depending apertured lugs carried by said axle-boxes, equalizing-bars passing through said apertured lugs, and extending beyond the wheel-base of the truck, springs supported upon the extended ends of said bars and 120 supporting said truck outside the wheel-base, and motor-supporting means carried by the truck-frame outside the wheel-base.

7. In a car-truck, the combination with the truck-frame, yokes or pedestals, outwardly-extending arms carried by said pedestals, angle-irons connecting said arms upon opposite sides of the truck, and a spring-supported 125 motor-frame mounted thereon: of axle-boxes embraced by said pedestals, equalizing-bars 130 extending beyond the wheel-base of the truck and suspended from said axle-boxes, and

- 4
- springs interposed between the extended ends of said bars and the frame outside the wheel-base thereof.
8. In a car-truck, the combination with the truck side frames, of transoms connecting said side frames, links suspended from said transoms, an upwardly-arched semi-elliptic spring connecting the free ends of the links, and a bolster extending over the spring and supported thereby at its center.
9. In a car-truck, the combination with the truck side frames, of transoms connecting said side frames, a bolster interposed between said transoms, links suspended from said transoms, a semi-elliptic spring connecting the free ends of said links, upon which said bolster rests, and helical springs interposed between the ends of said semi-elliptic springs and the ends of said bolster.
10. In a car-truck, the combination with the side frames, comprising axle-box pedestals, parallel upper and lower chords connecting said pedestals, a truss-bar extending between said pedestals, and a rectangular frame secured between said upper and lower chords and said truss-bar; of transoms carried by said rectangular frame, links suspended from said transoms, a bolster interposed between said transoms, and a semi-elliptic spring connecting the free ends of said links, and supporting said bolster at the center thereof.
11. In a car-truck, the combination with the side frames, comprising axle-box pedestals, parallel upper and lower chords connecting said pedestals, a truss-bar extending between said pedestals, and a rectangular frame secured between said upper and lower chords and said truss-bar; of transoms carried by said rectangular frame, links suspended from said transoms, a bolster interposed between said transoms, a semi-elliptic spring connecting the free ends of said links, and supporting said bolster at the center thereof, and helical springs interposed between the ends of said semi-elliptic springs and the ends of said bolster.
12. In a car-truck, the combination with a frame having yokes with outwardly-extending arms, axle-boxes embraced by said yokes but vertically movable therein, and having apertured depending lugs, equalizing-bars extending through the said apertures beyond the same and along the sides of the truck-frame, springs seated on said bars outside the wheel-base and bearing against the said arms to support the frame.
13. In a car-truck provided with wheels, axles and axle-boxes, a frame, means outside the wheel-base to spring-support the frame from the axle-boxes, and a motor-support, the free ends of which are supported on said frame, from a point outside the wheel-base of the truck.
14. In a car-truck having wheels, axles, and axle-boxes, equalizing-bars, a yoke-frame, means outside the wheel-base to spring-support the yoke-frame on the equalizing-bars, and a motor-support the free ends of which are resiliently supported on said frame, from a point outside the wheel-base of the truck.
15. In a car-truck having wheels, axles and axle-boxes, a frame, springs located outside the wheel-base and connected with said axle-boxes to support said frame, and means to support a propelling-motor from said frame outside the wheel-base.
16. In a car-truck, a truck-frame having yokes or pedestals, axle-boxes in said yokes, springs connected with said boxes to support said frame and located outside the wheel-base, and means to support a motor from said frame outside the wheel-base.
17. In a car-truck, a truck-frame having yokes or pedestals, axle-boxes in said yokes, springs connected with said boxes to support said frame and located outside the wheel-base, and a yielding or spring support for a motor on said frame outside the wheel-base.
18. In a car-truck, the combination with a frame having yokes with outwardly-extending arms, axle-boxes embraced by said yokes but vertically movable therein and having apertured depending lugs, equalizing-bars extending through the said apertures beyond the same along the side of the truck-frame, springs seated on said bars outside the wheel-base and bearing against the said arms to support the frame, and a spring-supported bar at one or both ends of said frame to act as a motor-support.
19. In a car-truck, a truck-frame comprising side members having upper and lower chords or parallel bars, inclined braces between said chords, a rectangular frame secured between said upper and lower chords midway of their length, transoms secured to said rectangular frames and extending across the truck-frame, a bolster movably mounted between said transoms, and links suspended from said transoms and supporting said bolster.
20. In a car-truck, a truck-frame comprising side members having upper and lower chords or parallel bars, inclined braces between said chords, a rectangular frame secured between said upper and lower chords midway of their length, transoms secured to said rectangular frames and extending across the truck-frame, a bolster movably mounted between said transoms, links suspended from said transoms, spring-seats carried by said links, a semi-elliptic spring having its ends resting in said spring-seats, and supporting the center of said bolster, and spiral springs, interposed between said links and the ends of said bolster.
21. In a car-truck, a bolster, separate and independent supports located near the ends of the bolster, means forming a connection between said supports to yieldingly sustain the bolster midway of its length, other means also connected with said supports to yieldingly sustain the said bolster at its ends.
22. In a car-truck, a truck-frame, a bolster

therefor, a semi-elliptic spring extending longitudinally beneath the same and supporting it at the center, separate and independent supports connected together by the ends of said springs and connected with the truck-frame, and other springs carried by said supports and bearing upwardly against the ends of the bolster.

23. In a car-truck, a bolster, transoms to confine the bolster, separate and independent supports depending from said transoms near the ends of the bolster, and springs beneath the bolster connected with the supports, one spring extending between the supports and having its ends connecting said supports, said spring bearing against the bolster at its center and the others bearing at its ends, either set being capable of supporting the bolster independently and both normally acting conjointly.

24. In a car-truck, a truck-frame having transoms extending across it, a bolster therebetween, links or stirrups extending from the said transoms below said bolster and forming supports, a semi-elliptic spring extending between said supports and bearing against the bolster midway between them, and another spring carried on each support to bear independently against the bolster.

25. In a car-truck, a truck-frame having transoms extending across it, a bolster therebetween, links depending from said transoms near each end of the bolster, and being connected across it, a semi-elliptic spring connecting said links and supporting the bolster at its middle point, and coil-springs also carried by said links and supporting the bolster at its ends.

26. In a car-truck, a bolster, springs to support the same at the center and ends, separate supports for the end springs, the center spring being carried by and connecting the same supports.

27. In a car-truck, a bolster, springs to support the same applied at the ends and at the center of the bolster, the ends or center springs being capable of conjoint or independent action to sustain the bolster, and an independent support near each end of the bolster for said springs, said supports being connected together by said center spring.

28. In a car-truck, in combination with the usual wheels, journal-boxes, and truck-frame, of equalizing-bars, a car-spring system having its ultimate support on said equalizing-bars, and a further set of springs supporting the ends of the truck-frame through means carried by extensions from the journal-boxes.

29. In a car-truck, the combination with the wheels and boxes, of a truck-frame, a car-spring system supported by the frame intermediate of the boxes, extensions from the boxes, spring-supporting means carried by said extension, and springs located between said extensions and the truck-frame.

30. In a car-truck, in combination, with the usual wheels, journal-boxes and truck-frame,

of car-supporting springs, equalizing-bars having ends extending outside of the journal-boxes, and springs carried in recesses adjacent said journal-boxes, and interposed between said ends and the truck-frame.

31. In a car-truck, in combination, with the usual wheels, journal-boxes, truck-frame, a car-spring system, and a set of springs located between the ends of the truck-frame and extensions resting in recesses in the journal-boxes.

32. In a pivotal car-truck, the combination with the usual wheels, and axles, and axle-boxes provided with depending portions; of yokes embracing said axle-boxes, the outside member of each of said yokes being provided with a recess, a helical spring located in each of said recesses, and equalizing-bars passing through said depending portions of said axle-boxes, upon which said springs rest.

33. In a pivotal car-truck, the combination with the usual wheels, axles, and axle-boxes; of side frames, transoms connecting said side frames, links depending from said transoms, a bolster located between said transoms, helical springs interposed between the ends of said bolster and supported by said links, and a semi-elliptic spring supporting the center of said bolster, the said spring connecting and supported by said links.

34. In a pivotal car-truck, the combination with the usual wheels, axles and axle-boxes; of side frames, transoms connecting said side frames, supporting means depending from said transoms, a bolster located between said transoms, helical springs interposed between the ends of said bolster and supported by said supporting means, and a semi-elliptic spring supporting the center of said bolster, the said spring connecting and being supported by said supporting means.

35. In a car-truck, the combination with the usual truck side frames, and transoms connecting said side frames; of links swinging from said transoms, spring-seats carried by said links, a bolster located between said transoms, a semi-elliptic spring connecting said links and supporting the center of said bolster, and helical springs interposed between said spring-seats, and supporting the ends of said bolster.

36. In a car-truck, the combination of the wheels, the journal-boxes, and an equalizing-bar supported by said journal-boxes, of a truck side frame, a rectangular frame mounted centrally within said side frame, springs interposed between said equalizing-bar and said side frame, a bolster and means for pivotally connecting said bolster and said rectangular frame.

37. In a car-truck, the combination of the wheels, journal-boxes, and an equalizing-bar carried by said journal-boxes, of a trussed side frame, comprising yokes or pedestals, a horizontal upper chord, and a lower chord, a brace extending from the tops of said yokes or pedestals and secured to the center of said

lower chord, and a rectangular frame interposed in said side frame between said upper chord and brace, a bolster and means for connecting said bolster and said rectangular frame.

38. In a car-truck, the combination of the wheels, journal-boxes, of a trussed side frame comprising yokes and pedestals, a horizontal upper chord, a lower chord, and a brace extending from the tops of said yokes and pedestals, and secured at the center of said lower chord, and a rectangular frame interposed in said side frame between said upper chord and brace, springs interposed between said equalizing-bar and side frames, a bolster, and means for pivotally connecting said bolster and said rectangular frame.

39. In a car-truck, the combination with the wheels and journal-boxes, and an equalizing-bar supported by said journal-boxes; of a trussed side frame, comprising axle-box yokes or pedestals, paired horizontal upper chords, one upon each side of the truck, lower chords beneath said upper chords, diagonal braces extending from the tops of the yokes or pedestals to the center of said lower chords, a pair of angle-iron transoms connecting said upper chords, a frame interposed between and connecting said transoms, and a bolsterspring supported between said transoms.

40. In a car-truck, the combination with the usual wheels and journal-boxes, and an equalizing-bar upon each side of the truck connecting said journal-boxes; of a truck side frame, comprising axle-box yokes or pedestals, a horizontal upper chord connecting the tops of said yokes or pedestals, a lower chord connecting the bottoms of said yokes or pedestals, a diagonal brace seated beneath said upper chord upon the tops of said yokes or pedestals, and having its center secured to the center of said lower chord, a rectangular frame including angle-iron transoms interposed between said upper chord and said lower chord and braces, and springs interposed between said equalizing-bar and said truck side frames.

41. In a car-truck, side frames with pedestals and axle-boxes, extensions from said axle-boxes outside the wheel-base, equalizer-bars, and equalizer-springs between said extensions and side frames, said springs being supported by said extensions.

42. In a car-truck, side frames with pedestals, axle-boxes guided in said pedestals and provided with spring-supporting means extending beyond the wheel-base, an equalizer-bar, and equalizer-springs between said frame and spring-supporting means, said springs being supported by said extensions.

43. In combination, in a truck, with a top frame, wheels, axles, pedestals and journal-boxes, an equalizer-bar upon each side of the truck, braces, angle-iron transoms, and a frame connecting said transoms, connected at its upper end to said top frame, and at its lower end to said braces.

44. In combination, in a car-truck with the usual top frame, wheels, axles, pedestals and journal-boxes, an equalizer-bar upon each side of the truck, and a lower chord and braces located above said equalizer-bars.

45. In combination, in a car-truck with the usual top frame, wheels, axles, pedestals, and journal-boxes, an equalizing-bar, a lower chord and braces located above said equalizing-bars, and connecting-pieces extending across the bottoms of the pedestals.

46. In a car-truck, side frames with pedestals, axle-boxes guided in said pedestals and provided with spring-supporting means extending beyond the wheel-base, equalizing-bars supported by said axle-boxes, and equalizing-springs between the side frame and spring-supporting means, said springs being supported by said extensions.

47. In combination, in a car-truck, with a top frame, wheels, axles, pedestals, and journal-boxes, an equalizing-bar, a truck side frame, and equalizer-springs resting upon the extended ends of said equalizing-bar, and supporting said truck side frame.

48. In combination, in a car-truck, with the usual top frame, wheels, axles, pedestals, and journal-boxes, of a truck side frame, an equalizing-bar, and equalizer-springs resting upon the extended ends of said equalizing-bar and spring supporting said truck-frame outside the wheel-base of the truck.

49. In combination, in a truck, with the usual wheels, axles, and journal-boxes; of an equalizing-bar, and a truck-side-frame spring supported upon the extended ends of said equalizing-bar.

50. In combination, in a car-truck, with the usual wheels, axles and journals; of an equalizing-bar supported by said journal-boxes, a truck side frame, and springs interposed between the extended ends of said equalizing-bar and side frame and resting on said equalizing-bar.

51. In combination, in a car-truck, with the usual wheels, axles, and journal-boxes; of an equalizing-bar supported by said journal-boxes, truck side frames, and means located entirely outside the wheel-base of the truck for supporting said truck-frame from said equalizing-bar.

52. In combination, in a truck-frame, with the usual wheels, axles and journal-boxes, of an equalizing-bar, a truck side frame, angle-iron transoms connecting said side frames, and springs interposed between said equalizing-bar and side frames outside the wheel-base thereof, and resting on said equalizing-bar.

53. As an article of manufacture, a side frame for trucks consisting of yokes, an upper chord connecting said yokes, lugs on the inner arms of said yokes, but intermediate of their ends, a lower chord connecting said lugs, a frame, a bracing connecting said upper and lower chords and frame.

54. As an article of manufacture, a side

frame for trucks containing yokes, upper and lower chords containing said yokes and a bracing connecting said yokes and upper and lower chords, a frame connecting said bracing with the upper chord, and brackets integral with said frame.

55. As an article of manufacture, a side frame for trucks containing yokes, chords connecting said yokes, extensions on the outer arms of said yokes, and inverted cups on said extensions forming housings for springs.

56. As an article of manufacture, a side frame for trucks containing yokes, chords connecting said yokes, extensions on the outer 15 arm of the yokes, inverted cups forming housings on said extensions, and openings in said housings.

57. As an article of manufacture, a side frame for trucks containing yokes, lugs on the 20 inner arms of the yokes and intermediate of their ends, lower chords connecting said lugs and upper chords connecting the yokes.

58. As an article of manufacture, a yoke formed in one integral piece containing an arm with a projecting lug intermediate of its ends, a second arm with an extension provided with an inverted opening forming a housing for a spring.

59. In a car-truck, the combination of the side frames, equalizing-bars, springs outside the wheel-base supporting said frames, a bolster, and a transverse spring supporting said bolster.

Signed at the city of Hot Springs and county of Bath, State of Virginia, this 10th day of May, 1901.

JOHN A. BRILL.
WALTER S. ADAMS.

Witnesses as to John A. Brill:

R. W. BRAGG, Jr.,
CHARLES E. WOOD.

Witnesses as to Walter S. Adams:

VINCENT ANDERSON,
HENRY C. ESLING.
